UNITED STATES PATENT OFFICE

VIRGIL L. FRANTZ AND OREN O. LEMON, OF ROANOKE, VIRGINIA, ASSIGNEES TO SAID
FRANTZ

LOCOMOTIVE SANDING DEVICE

Application filed February 13, 1929. Serial No. 339,715.

The invention relates to means for applying sand to the rails beneath the traction wheels of locomotives or the like.

In Patent No. 1,263,722 granted to William H. White on April 23rd, 1918, there is disclosed a locomotive sanding device embodying a sand box or dome from which lead sand pipes connected with sand traps having discharge pipes leading therefrom to points in advance of the driving wheels of the locomotive. The sand is forced out by compressed air controlled by a suitable valve means within the locomotive cab. In this particular device and in others of a more or less similar nature, the sand trap has therein a nozzle from which compressed air discharges for forcing the sand through the delivery pipes. These devices also include cleaning means generally consisting of a port located opposite the entrance to the delivery pipe and receiving compressed air from a separate pipe, the purpose being to prevent clogging of the delivery pipe. In devices of this nature it is customary to provide a valve for controlling the flow of compressed air successively to the cleaning pipe and discharge jet, the valve being manually operable to control the flow of pressure.

The present invention has for its principal object the provision of a valve located within the compressed air line to the sand trap and connected with the cleaning pipe, this valve acting to permit the passage of compressed air for a short period of time to the cleaning pipe and port and then automatically closing so that the compressed air will be subsequently supplied to the discharge jet only.

An important object of the invention is to provide a valve of this character which requires no manual control but which is actuated involuntarily by a manually operated sanding valve to remotely control automatically the supply of compressed air to the cleaning pipe and port.

Another important object of the invention is to provide a sanding device embodying a valve of this type of such construction that it will remain open for a predetermined period to insure the proper flow of compressed air to the cleaning pipe or port, the

valve also having means for cushioning its action and preventing slamming or premature closing.

Another object of the invention is to provide a valve of this type which is normally open and provided with means for returning it to open position after actuation by air pressure so that it will be ready for a repeated action.

An additional object of the invention is to provide a mechanism of this character which will be simple and inexpensive to manufacture, easy to install, positive and automatic in action, durable in service, and a general improvement in the art.

To the attainment of the foregoing and other objects and advantages, the invention preferably consists in the details of construction and the arrangement and combination of parts to be hereinafter more fully described and claimed, and illustrated in the accompanying drawing in which:

Figure 1 is a diagrammatic elevation of a locomotive equipped with sanding means for forward and also reverse movement, an embodiment of the invention being shown in applied position.

Figure 2 is a vertical longitudinal section through the automatic valve alone.

Figure 3 is a cross sectional view therethrough taken on the line 3-3 of Figure 2, and

Figure 4 is a cross section taken on the line 4-4 of Figure 2.

Referring more particularly to the drawing, the numeral 1 designates, generally, a portion of a locomotive having the usual driving wheels 2. The numeral 3 designates a sand box or dome which is mounted on top of the boiler as is customary and which contains sand conducted through the sand pipes 4 to sand traps 5 and 6 from which lead delivery pipes 7 and 8, the former being provided for the purpose of conducting or delivering sand in advance of the driving wheels and the latter being for the purpose of conducting sand to the rear thereof when the locomotive is operated in reverse. The sand traps, sand pipes and delivery pipes are provided at both sides of the locomotive

as will of course be readily understood and it is naturally intended that the action will be the same at both sides whether the locomotive be running forwardly or rearwardly. In view of the disclosure in Patent No. 1,263,722 granted April 23rd, 1918, to William H. White it is thought unnecessary to illustrate the construction of the sand traps as a full understanding in regard thereto may be had by inspecting said patent. It is thought sufficient for present purposes to state that compressed air is supplied to the discharge jets within the traps 5 and 6 through pipes 9 and 10 respectively, and that compressed air is supplied to the cleaning ports through pipes 11 and 12 respectively. The discharge pipes 9 and 10 at each side of the locomotive are connected by transverse pipes 13 and the cleaning pipes 11 and 12 at each side are similarly connected by pipes 14. As mentioned above, the usual practice is to provide manually operated valve means for controlling flow of compressed air to the pipes 11 or 12, and 9 or 10, successively, this depending upon the direction of movement of the locomotive. The objection to manual means of this type, such as disclosed in the above mentioned White Patent No. 1,263,722, is that the engineer may permit compressed air to pass to the cleaning pipes and ports for either too long or too short a time. If the time is too short the delivery pipes may not be properly unclogged and if the time is too long there is a waste of compressed air. As a matter of fact we have not shown any manual valves for controlling the passage of compressed air to the sanding devices as this is a detail immaterial in the present combination.

In accordance with the invention we provide automatic valves indicated generally at 15 and 16 interposed between the cleaning pipes 11 and 12 and the supply pipes 17 and 18 respectively which are equipped with any suitable control valves, not shown. The discharge pipes 9 and 10 are connected with the supply lines 17 and 18 respectively in advance of the automatic valves 15 and 16 as clearly indicated in Figure 1. The valves 15 and 16 are identical in construction so that a description of one will suffice and it should be mentioned at this point that they are normally open.

Each of the valves 15 and 16 is shown as comprising a body 19 having an inlet 20 at one side and having an outlet 21 near its bottom or one end. Internally the body is formed with a valve seat 22 at one end of a bore or socket 23 which leads to the outlet 21, and this seat is adapted to be engaged and closed by a valve 24 above or adjacent which are guide vanes or ribs 25 beyond which is a piston 26. The valve 24 is adapted to permit or cut off communication between the inlet 20 and the outlet 21 and is normal-

ly held in open or unseated position by a spring 27 located within the bore or socket 23 and engaging against the end or underside of the valve. As it is desired to retard or cushion the closing movement of the valve 24, a vacuum producing means is provided, this means comprising a cap 28 secured to the body 19 and formed with a cylinder 29 within which the piston 26 is slid able. The diameter of the piston and cylinder should be less than that of the valve 24 for obvious reasons and it is preferable that the piston 26 be cored out or otherwise provided with a hollow portion or chamber 30 so as to avoid the formation of too high a vacuum to permit closing of the valve in the manner to be described.

Assuming that the entire apparatus has been assembled and installed upon a locomotive as shown in Figure 1, and as described, and likewise assuming that the automatic valves are in their proper relation to the other parts as shown, the operation is as follows:

When whatever valve provided for the pipes 17 or 18 is opened, air will pass to and through the valve 15 or 16, as the case may be. As the air rushes through the auxiliary valve the pressure upon the movable valve member 24 combined with the frictional drag resulting from passage of air about the valve 24 will cause it to move downwardly into engagement with its seat 22. As long as the valve 24 is unseated the air passing through the auxiliary valve device flows to the cleaning pipe or port. The time required for the pressure and frictional drag to cause seating of the valve 24 is comparatively slight so there is not much more than a momentary cleaning blast. When the valve member 24 tends to seat movement is retarded and slaming prevented by the partial vacuum formed behind or above the piston 26. The relation of the diameter of the piston to that of the valve 24 should be so gauged as to avoid possibility of failure of the valve member 24 to close or seat but this is a detail which may be readily worked out either by trial or computation. Just as soon as the valve member 24 seats, the cleaning blast ceases and the air then passes only through the discharge pipe 9 or 10, as the case may be, so that sand will be forced out through the delivery pipes 7 or 8. Air pressure continues to flow through these discharge pipes and delivery pipes until whatever valve provided in the pipes 17 or 18 is cut off but the auxiliary or automatic valve remains closed until this air pressure is cut off whereupon the spring 27 will return the movable valve member 24 to its normal open position,

the action of the spring being assisted by the tendency of the partial vacuum formed in the chamber 29 to draw the piston 26 thereinto.

From the foregoing description and a study of the drawing it will be apparent that we have thus provided a very simple valve mechanism by means of which a certain predetermined blast may be permitted to flow through the cleaning port for the purpose of preventing clogging of sand in the delivery pipe. It will be noted that there is no voluntary action on the part of the engineer required to effect the necessary cleaning.

The mechanism is consequently safeguarded against carelessness or forgetfulness on the part of the engineer and the entire mechanism should consequently remain in much better working order than would otherwise be the case. It is believed that the construction, operation and advantages will be readily apparent from the above without further explanation.

While we have shown and described the preferred embodiment of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described the invention, we claim:

1. In a locomotive sanding mechanism including a sand dome, sand traps receiving sand from the dome and having delivery pipes connected therewith, each sand trap having a cleaning pipe leading thereto and having a sand discharge pipe leading thereto, a compressed air supply pipe, and an automatic valve interposed between each cleaning pipe and supply pipe beyond the point of connection of the discharge pipe with the supply pipe, said automatic valve being normally open and being adapted to close under the influence of air pressure whereby an initial blast of predetermined duration will be permitted to flow through the cleaning pipe.

2. In a locomotive sanding mechanism, the combination of a sand dome, a sand trap receiving sand therefrom, a sand delivery pipe leading from the sand trap, a cleaning pipe connected with the sand trap, a compressed air supply pipe leading to the sand trap, and a normally open valve interposed between the supply pipe and the cleaning pipe, said valve being operated by pressure and frictional drag of compressed air passing therethrough for cutting off communication between the supply pipe and the cleaning pipe whereby only a blast of short duration will be permitted through said cleaning pipe.

3. In a locomotive sanding mechanism, the combination of a sand dome, a sand trap receiving sand therefrom, a sand delivery pipe

leading from the sand trap, a cleaning pipe connected with the sand trap, a compressed air supply pipe leading to the sand trap, and a normally open valve interposed between the supply pipe and the cleaning pipe, said valve being operated by pressure and frictional drag of compressed air passing therethrough for cutting off communication between the supply pipe and the cleaning pipe whereby only a blast of short duration will be permitted through said cleaning pipe, said valve embodying means for retarding its closing movement.

4. In a locomotive sanding mechanism, the combination of a sand dome, a sand trap receiving sand therefrom, a sand delivery pipe leading from the sand trap, a cleaning pipe connected with the sand trap, a compressed air supply pipe leading to the sand trap, and a normally open valve interposed between the supply pipe and the cleaning pipe, said valve being operated by pressure and frictional drag of compressed air passing therethrough for cutting off communication between the supply pipe and the cleaning pipe whereby only a blast of short duration will be permitted through said cleaning pipe, said valve embodying partial vacuum creating means for retarding its closing movement.

5. In a locomotive sanding mechanism including a sand trap having a delivery pipe, a cleaning pipe and a fluid pressure supply pipe connected therewith, the combination of normally open fluid pressure closed means interposed between the supply pipe and the cleaning pipe for permitting a blast of short duration through the latter.

6. In a locomotive sanding mechanism, the combination of a sand dome, a sand trap receiving sand therefrom, a sand delivery pipe leading from the sand trap, a cleaning pipe connected with the sand trap, a fluid pressure supply pipe leading to the sand trap, and a normally open valve interposed between the supply pipe and the cleaning pipe, said valve comprising a body having its inlet and outlet connected with the supply pipe and cleaning pipe respectively and having a seat between the inlet and outlet, a valve member movably mounted within the body and responsive to pressure therein and frictional drag resulting from passage of air therethrough to engage said seat and cut off communication between the supply pipe and the cleaning pipe.

7. In a locomotive sanding mechanism including a sand trap having a delivery pipe, a cleaning pipe and a fluid pressure supply pipe, a normally open valve interposed between the supply pipe and the cleaning pipe comprising a body having an inlet and an outlet connected respectively with the supply pipe and cleaning pipe and having a seat between the inlet and outlet, a valve

member movably mounted within the body and responsive to pressure therein and frictional drag resulting from passage of air therethrough to engage said seat and cut off 5 communication between the inlet and the outlet, spring means normally holding the valve member unseated, and means for retarding closing movement thereof.

8. In a locomotive sanding mechanism including a sand trap having a delivery pipe, a 10 cleaning pipe and a fluid pressure supply pipe, the combination of a valve device comprising a body having an inlet and an outlet connected respectively with the supply pipe 15 and cleaning pipe, the body being provided between the inlet and outlet with a valve seat, a valve member movably mounted within the body and responsive to pressure therein and frictional drag resulting from passage 20 of air therethrough to engage said seat and cut off communication between the inlet and the outlet, spring means normally holding the valve unseated, and means for retarding closing movement comprising a piston carried by the valve member, and a chamber 25 within which said piston is slidably whereby a partial vacuum will be formed during movement of the valve member to seated position.

30 9. In a locomotive sanding mechanism, the combination with a valve casing having a plurality of ports entering a common chamber, a fluid pressure supply pipe connected to only one of said ports and a cleaning pipe 35 connected to another of said ports, a valve mechanism within said chamber including a longitudinally movable member adapted to be actuated by fluid pressure entering said chamber through said fluid pressure supply 40 pipe, said member being adapted to cut off the supply of fluid pressure to said port leading to the cleaning pipe after a predetermined interval of time.

10. In a locomotive sanding mechanism, 45 the combination with a valve casing having a plurality of ports entering a common chamber, a fluid pressure supply pipe connected to one of said ports and a cleaning pipe connected to another of said ports, a valve mechanism within said chamber including a longitudinally movable member and spring means 50 for normally maintaining said member in position to permit the flow of fluid pressure through said chamber to said cleaning pipe, said longitudinally movable member being adapted to be actuated by fluid pressure entering said chamber through said fluid pressure supply pipe to cut off the supply of fluid pressure to said port leading to the cleaning pipe 55 after a predetermined interval of time.

11. In a locomotive sanding mechanism, 60 the combination of a valve casing having inlet and outlet ports communicating with a common chamber in the casing, the inlet port 65 being located at substantially the center of

the chamber and the outlet port being located between the inlet port and one end of the chamber, a fluid pressure supply pipe connected to said inlet port, a cleaning pipe connected to said outlet port, and valve means within said casing normally permitting communication between the fluid pressure supply and the cleaning pipes and movable longitudinally by fluid pressure admitted to said chamber through said supply pipe for cutting off communication to said cleaning pipe after a predetermined interval of time.

70 12. In a locomotive sanding mechanism, the combination of a valve casing having inlet and outlet means communicating with a common chamber at substantially the center and toward one end thereof respectively, fluid pressure supply and cleaning pipes connected to said respective means, and means within said casing normally unobstructing said outlet means and movable longitudinally by fluid pressure admitted to said chamber through said inlet means for closing said outlet means after a predetermined interval of time.

75 80 In testimony whereof we affix our signatures.
